UNITED STATES PATENT OFFICE.

WILLIAM J. P. MOORE, OF NEW YORK, N. Y.

RADIATOR SUSPENSION.

1,282,451.

Specification of Letters Patent. Patented Oct. 22, 1918.

Application filed September 12, 1916. Serial No. 119,620.

To all whom it may concern:

Be it known that I, WILLIAM J. P. MOORE, a citizen of the United States, and resident of New York, in the county of New York 5 and State of New York, have invented certain new and useful Improvements in Radiator Suspensions, of which the following is a specification, reference being had therein to the accompanying drawing.

10 This invention has to do with radiators for automobiles and the like, which contain a circulating fluid for cooling the action of the engine; and it relates more particularly to the means for suspending the radiator in 15 or upon the frame of the car.

The object is to enable the radiator to be supported in such a manner that there will be some substantial amount of give or flexibility in the support, so that the radiator 20 may accommodate itself in its position to the torsional and other strains to which it is subjected under the vibration of the engine and the twisting and turning of the car; and also 25 the invention relates to a radiator suspension which enables it to be easily removed and replaced as the exigencies of repair or inspection work may be determined at various times.

The invention, therefore, comprises essentially a removable radiator member, in combination with a suspending saddle which is carried by the frame of the automobile or other machine, there being preferably interposed between the radiator and the saddle a 35 cushioning member of rubber, felt, asbestos, or other suitable fabric or material, and there being a suitable number of securing devices which fasten the radiator within the saddle; and also the invention comprises numerous details and peculiarities in the 40 construction, arrangement, and combination of the various parts, substantially as will be hereinafter described and then more particularly pointed out in the ensuing claims.

45 In the accompanying drawing illustrating my invention:

Figure 1 is a front elevation of my improved radiator suspension mechanism.

Fig. 2 is a similar front elevation of the 50 radiator and its suspension means removed from the front frame work of the automobile.

Fig. 3 is a vertical section on the line 3, 3 of Fig. 1, certain parts being in side view.

55 Fig. 4 is a side elevation of the saddle that surrounds and receives the radiator,

Fig. 5 is an enlarged detail section of the lower end of the radiator and saddle as indicated at the bottom of Fig. 3.

Fig. 6 is an enlarged horizontal sectional 60 plan on the line 6, 6 of Fig. 3.

Similar characters of reference designate corresponding parts throughout the different figures of the drawing.

It is unnecessary to enter here into any 65 complete description of the radiator proper, inasmuch as it may be any one of the great variety of radiators that are now in well-known use, or any other kind of radiator, the same having the customary function of automobile radiators and being made up of a multiplicity of tubes through which the cooling water circulates. I have designated a specimen of radiator here, as 5, the same being of oval or egg-shaped form, smaller at 70 the top and broader at the bottom, and having the customary water circulating pipes, one of which, as 6, enters the radiator near the top, while the other, as 7, enters near the bottom. This radiator 5 when in use occupies an up- 75 right position in the front portion of the frame contiguous to the engine, which latter is not shown.

1 designates the upper part of a cover in which the radiator is suspended. This may 80 obviously have a wide variety of different forms, but in the particular example which I have used to illustrate the invention, it corresponds generally to the shape of the radiator, being generally bow-shaped, with 85 its sides resting upon and secured to the sides 2, 2 of the main frame. The details of the latter are not brought out in the drawings, as it is unnecessary to present them. Said sides 2 are shown, however, provided 90 with the side covers 3, 3 which are used with my particular novel type of frame wherein these sides 2, 2 are provided with housings 95 for completely enveloping and protecting the springs and their appurtenant parts. 100

Within the cover 1 I locate the saddle consisting of an arching or bow-shaped plate 8 having parallel vertical flanges 8^a at both the edges thereof, and terminating in a base 4 having a straight lower edge 4^a and cut-out 105 vertical sides 9 which receive the covers 3 of the sides 2 of the frame. The saddle also has projections 10 above the covers 3 which fit against the sides of the frame, and are there united to the frame by welding or 110 otherwise, while at the bottom of the member 4, or at the opposite ends of its bottom

edge 4^a, are also similar projections 11 which fit against the sides of the frame 2 below the covers 3, where said projections are united to the frame by welding or otherwise, 5 so that the whole saddle may thus be properly positioned within the encircling and sustaining framework. It is further to be noted that the arch or bow-shaped plate 8 has an oval form which corresponds to the general 10 shape of the radiator; that is, the basal portion 4 is so shaped that in cross-section it exhibits flanges 4^b which are much wider than the flanges 8^a which run from a point near the projections 10 around the upper portion 15 of the arch 8, as indicated in Figs. 3 and 4. It is desirable that the saddle should be made of this light steel construction having the main arch plate 8 with the parallel flanges at the edges which take the narrow 20 form 8^a throughout a portion of the length and then widen out at the bottom into the parts 4^b so as to make a substantial basal member which can be upheld in the sides of the frame in the way that I have described. 25 While the lower portion of the saddle is held in the frame by the engagement of the projections 10 and 11 with the sides of the latter, it will be seen by referring to Fig. 3, that the narrow flanges 8^a fit neatly under 30 beneath the upper arching cover 1, and that the outermost flange 8^a is held firmly against a bead 1^a which is located around the inside front edge of the front cover 1. Additional or other means for holding the saddle in the 35 frame may also be utilized.

Between the saddle and the radiator I interpose an endless cushion 12, which may be a strip of rubber, asbestos, or any other suitable fabric or material, being in a measure 40 elastic and serving to cushion the contact between the radiator and the saddle and to impart to the joint a greater or less amount of flexibility or resiliency so that the two parts may not be held together with too 45 much rigidity, but will be so related that the radiator will have some slight amount of yielding character or give under the different strains to which it is subjected. The thickness and width of the strip 12 may 50 vary within wide limits, and I do not wish to be restricted in this respect. Furthermore, it may pass entirely around the radiator between the latter and the saddle, that is to say, it may effectually line the whole in- 55 terior of the oval-shaped plate or framework 8, or in some cases it may run only a part of the way around, different examples of construction requiring different material in this regard, and I wish the liberty of 60 changing and varying as may be required, and further, it may be desirable to arrange this intervening cushion in a number of layers instead of simply one, and the layers may be of the same or different materials, 65 and various other changes and alterations

in this interposed cushion may be made without exceeding the main intent of the invention.

The saddle and radiator with the intervening cushioning material are held together by 70 a plurality of devices located at points suitably distanced from each other, of which there may be as many or as few as will effectively do the work. I find it convenient to use two of these devices at the top of the 75 radiator, one at each side and two at the bottom. They consist of bolts 13 (see Fig. 5) having heads 14, which bolts pass through openings 15 in the radiator wall and corresponding coincident openings in the contiguous plate 8, while the inner threaded ends of these bolts 13 engage mushroom nuts 16 whose inner faces are welded or brazed against the adjoining side of the radiator to prevent 80 leakage. These bolts are preferably inserted 85 centrally in the width of the radiator and saddle and are accessible from the outside of the saddle, as shown in Figs. 4 and 5, and caused to pass through first the saddle, then the interposed packing 12, then the wall of 90 the radiator, and then are brought into engagement with the welded nuts 16. These devices are, however, given herein by way of example and any other suitable bolt, clamp, or equivalent securing means, may be 95 adopted for the same purpose. These devices hold the radiator firmly within the saddle, and as the saddle is rigidly sustained in the frame, the parts are all tightly joined together, and yet the suspension of the radiator 100 is such that it is able to accommodate itself to the severe strains, torsional, and otherwise, to which it is subjected under the heavy vibration of the engine and the severe twisting to which the parts of the car are exposed in the running of the machine. It will 105 be found that a suspension for the radiator like what I am now describing will possess, therefore, many very useful and valuable features over more rigid forms of radiator 110 which are now in use. Obviously the radiator can be quickly and easily removed and replaced by simply taking out the bolts, and further the semi-elastic cushioning 12 between the radiator and its suspension saddle can be 115 renewed whenever desired by simply taking out the radiator and putting in a new strip so that the effectiveness of the member 12 can be maintained at all times.

Many changes in the precise construction, 120 arrangement, and relation of the various parts may be made without exceeding the scope of the invention, and I reserve the liberty of making all such changes, additions, and substitutions as may be found desirable 125 and useful in practice.

Having thus described my invention, what I claim as new and desire to secure by Letters Patent, is:—

1. In a radiator suspension, the combina- 130

tion with a supporting frame, a saddle shaped with a plate conforming to the radiator, and having an upper arching portion and basal portion, both of skeleton form, a radiator 5 adapted to be inserted in the saddle, an interposed strip of fabric material between the radiator and the saddle, and a series of clamping bolts that pass through the saddle, the fabric and the radiator wall for holding 10 the parts together.

2. In a radiator suspension, the combination of an automobile frame, a saddle attached thereto and consisting of an endless plate shaped to conform to the figure of the 15 radiator and having supporting flanges and a flanged basal portion, a radiator carried in the said endless plate, and a sheet of non-metallic substance interposed between the radiator and the saddle, and means for holding 20 the saddle, radiator, and sheet together.

3. The herein described means for yieldingly sustaining an automobile radiator consisting in the combination with a frame, of a saddle attached thereto and shaped to receive 25 the radiator when laterally inserted thereinto from the front or rear, said saddle having front and rear parallel vertical flanges, and also bottom flanges that form a base, a radiator removably inserted in the saddle, 30 and an intervening layer of non-metallic material between the radiator and the saddle, and clamping means for holding the saddle, radiator, and layer together.

4. In a radiator suspension, the combination with supporting means carried on an automobile, of a saddle consisting of an endless flanged member forming an arch at the top 35

and a wider basal portion below and attached to the supporting means, a radiator properly shaped for insertion into the correspondingly-shaped wall of the saddle, and an interposed strip of fabric between the radiator and the saddle, together with a series of clamping devices passing through openings in the radiator, saddle and fabric. 40 45

5. In a radiator suspension, the combination with supporting means carried on an automobile, of a saddle consisting of an endless flanged member forming an arch at the top and a basal portion below and attached to the supporting means, a radiator properly shaped for insertion into the correspondingly-shaped wall of the saddle, and an interposed strip of fabric between the radiator and the saddle, together with a series 50 55 of bolting devices passing through openings in the radiator, saddle, and fabric.

6. In a radiator suspension, the combination with an automobile frame, of a saddle consisting of a vertical member formed as a flanged arch at the top and with a basal portion below, said basal portion consisting of parallel flanges on the saddle and having pairs of ears at each side for attachment to the frame, a radiator inserted into the similarly shaped wall of the saddle, and a cushion intermediate between the radiator and the saddle, together with a series of securing devices passing through openings in the radiator, saddle and cushion. 60 65 70

In testimony whereof I hereunto affix my signature.

WILLIAM J. P. MOORE.
